FREDERICK L. WHITE, OF LAKEWOOD, OHIO, ASSIGNOR TO NATIONAL CARBON COMPANY, A CORPORATION OF NEW JERSEY.

DRY CELL.

1,196,999.

Specification of Letters Patent. Patented Sept. 5, 1916.

Application filed September 12, 1914. Serial No. 861,452.

To all whom it may concern:

Be it known that I, FREDERICK L. WHITE, a citizen of the United States, residing at Lakewood, in the county of Cuyahoga and State of Ohio, have invented a certain new and useful Improvement in Dry Cells, of which the following is a full, clear, and exact description.

This invention relates to a waterproof insulating coating for dry cells having pasteboard jackets. When used in moist climates, motor boats, etc., the jackets sometimes are wetted, especially at the bottom to such an extent that they become electrically conductive and short circuit the zinc container electrodes of adjacent cells. Also the water causes the joints to become unglued and the jackets to fall off.

All prior methods of waterproofing are disadvantageous because they are too expensive, do not perform their functions completely, or give the cells a poor appearance. Difficulties occur principally with the bottom of the jackets when the battery box case becomes partially filled with water. After setting in water for any considerable time the water soaks through any portion where the coating has been damaged, and to obviate this trouble I treat a dry cell as illustrated in the accompanying drawings in which:—

Figure 1 is a perspective view of a dry cell treated by my waterproofing process. Fig. 2 is a partial sectional view of the bottom of the jacket.

Referring to the drawings, 1 represents the pasteboard jacket and 2 the paper cap which closes the bottom. The bottom of the jacket is dipped into a heated waterproofing compound 3 consisting of approximately 49% of hard pitch, 44% of soft pitch and 7% of scale wax to cover the cap completely. When this compound cools it forms an elastic waterproof coating entirely covering the outside of the cap. This coating is relatively thick and sufficiently elastic so that it will not chip off.

Although I have set forth a certain composition for coating the cap, it will be evident that other suitable materials or compositions may be used. For instance, in cool weather I use a compound having a greater percentage of soft pitch, as 44% of hard pitch, 49% of soft pitch and 7% of scale

wax. Under these climatic conditions this compound has the same properties as the first material. Other compounds may be used but I prefer the composition set forth.

When the previous compounds alone are used they become sticky in warm weather and cause the bottom of the cell to adhere to paper, straw and other packing material in their shipment, giving them an unsightly appearance. To prevent this, as well as to make the rest of the jacket waterproof, I immerse the entire jacket in melted scale wax to form a coating 4 over the entire article. This coating also prevents the pitch from being chipped off when it becomes hardened in cold weather. A temperature of 70 degrees centigrade for the melted wax is found to be preferable for impregnating the jackets, because at higher temperatures the glue used in making the jacket is deleteriously affected, and at lower temperatures the impregnation cannot be carried on as well. It will be evident that other well known waterproof coatings may be used instead of scale wax.

After the jacket has been prepared in the manner described, the dry cell is inserted therein and the entire article is again immersed in melted scale wax to completely cover it with a waterproof coating, which gives the cell a neat glossy appearance. The scale wax coating being transparent, the label is printed directly on the jacket in the usual way, and an extra label is not required as with opaque coatings. The cell is especially advantageous where only a small amount of water is present in the bottom of the battery box. In most cases this condition, rather than the complete immersion of the cell, is encountered. A cell having a coating of pitch and wax at the bottom will withstand the action of water indefinitely and can be more cheaply made than a cell entirely covered with a compound such as the pitch material described. Although I may coat the entire cell with this compound, it is disadvantageous on account of the extra label required, as well as the extra expense.

Having described my invention, what I claim is:—

1. The process of water-proofing a dry cell jacket having a cap for closing the bottom, which consists in applying a coating of

elastic material to cover the cap and afterward applying a coating of wax to the exterior of the jacket and cap.

2. The process of water-proofing a dry cell jacket having a bottom cap, which consists in dipping the jacket in melted pitch adapted to become elastic upon cooling, and then impregnating the entire jacket by immersing in wax heated to a temperature of 10 approximately 70° C.

3. The process of water-proofing a dry cell which consists in coating the bottom portion of a jacket with an elastic insulating material, impregnating the entire jacket 15 with wax, inserting the cell in the jacket and immersing the entire article in melted wax.

4. A water-proof pasteboard jacket for a dry cell having a bottom, an elastic coating on said bottom, and a coating of wax applied 20 to the jacket and first mentioned coating.

5. A dry cell having an inclosing jacket, a bottom cap, a coating of elastic material on the bottom of said jacket extending above

the junction between the cap and jacket, and 25 a coating of wax applied to said jacket and first mentioned coating.

6. A dry cell having an inclosing jacket, a bottom cap, a coat of elastic material on the bottom of said jacket extending above the 30 junction between the cap and jacket, a coat of wax applied to said jacket, and a second superimposed coat of wax applied to the jacket and top of the cell.

7. A dry cell having an inclosing jacket, 35 a paper cap closing the bottom of the jacket, a coating of elastic pitch on said cap and extending above the junction between the cap and jacket, and a coating of wax applied to said jacket and first mentioned 40 coating.

In testimony whereof, I hereunto affix my signature.

FREDERICK L. WHITE.
